IGNITION OF FUEL FOR LIGHTING A WELL

Orin G. Kaasa, Tulsa, Okla., assignor to Sinclair Oil & Gas Company, Tulsa, Okla., a corporation of Maine

Filed Sept. 26, 1956, Ser. No. 612,143

16 Claims. (Cl. 166—38)

This invention relates to the heating of underground formations, and, more particularly, the invention is concerned with a method for heating or lighting a subterranean stratum opposite a well bore through contact in the bore of water and a chemical substance reactive with water to provide a spontaneously ignitable reaction product in the vicinity of the stratum to be heated. This product is mixed with a free-oxygen-containing gas and a hydrocarbon fuel to provide combustion.

It has been proposed to heat underground formations for various purposes usually associated with increasing recovery of oil by secondary recovery methods. For instance, heat may be applied in the immediate vicinity of a well bore to lower the viscosity of surrounding hydrocarbon materials. A more important use of the heating lies in connection with in-situ combustion procedures. In a particularly advantageous method of this type, a fuel such as methane is combusted in an input well bore to heat the first few feet of adjacent petrolierous stratum to a temperature generally greater than about 400° F., e.g. about 600 to 1200° F., to establish combustion in the stratum. This procedure is often referred to as well lighting. In one recovery method a cooling gas which will not support combustion can then be injected and as a result the heat front is moved into the formation away from the input well bore. A free oxygen-containing gas is subsequently injected to move the combustion front towards one or more output wells. By this method the hydrocarbon content of the formation is moved towards the output well, and substantially all of the oil can be swept from the formation traversed by the combustion or heat wave.

Usually in well heating or lighting procedures a burner device is lowered into the well to the vicinity of a bare formation which is to be heated or lighted. Aside from having to provide an apparatus which satisfactorily mixes and burns air and fuel in the well for initiating combustion in the stratum, considerable difficulty has been experienced in providing conditions conducive to the initial heating of the fuel and oxygen-containing gas to combustion temperatures. Sometimes a sparking device is employed as a means for igniting a hydrocarbon fuel-air stream. Difficulties arise in these devices due to complications in burner structure and the fact that the operator is several hundred feet from the level of burning. Depending upon the location and depth of the well, elevated pressures and temperatures may be encountered which affect the operation of the burner. Also electrical conductors must be employed and this gives rise to problems concerned with stringing the conductors and proper construction as to wire sizes and electrical and thermal insulation. Needless to say, these various factors can be responsible for excessive costs and difficulties in operation, particularly as the operator increases the distance the burner is projected into the well bore.

In the method of the present invention for heating or lighting a subterranean stratum many of the disadvantages of prior methods are avoided. In my method I contact in

2

the vicinity of the stratum water and a chemical substance or material which reacts with the water to afford a spontaneously combustible product. The water and reactive material are both conveyed in moving fluid streams to the location of contact. The reaction product is combusted in free oxygen supplied to the vicinity which in turn ignites a liquid or gaseous hydrocarbon fuel made available. In one embodiment, a suitable reactive material, e.g. calcium phosphide, is added to the well bore 5 through a tubing carrying a free oxygen-containing gas and water is then immediately injected into the tubing so that the reactive material and water will contact at or near the location of the well stratum to be heated. The mixing of the water and reactive material provides a spontaneously ignitable product which combusts in oxygen provided. The initial combustion is then effective to burn the hydrocarbon fuel in the oxygen present. After combustion of the hydrocarbon fuel is established, the water and reactive material injections can be stopped, and combustion of the hydrocarbon fuel can be continued until the adjacent stratum is sufficiently heated. During the addition of the reactive material, I have found it advantageous to increase the velocity of the gas stream carrying the reactive material as compared with the velocity employed while injecting the water. This is particularly useful where the normal flow velocity which is employed during water injection is of a relatively low order. When the flow velocity is increased during the addition of the reactive material, I prefer that this velocity be at least about twice that employed during the water injection. A particular advantage of my method lies in its ability to be used under diverse well conditions, for instance temperatures of about 50 to 350° F. or more and pressures from about atmospheric to 10,000 lbs. or more. 10 20 25 30 35 40 45 50 55 60 65 70

Perhaps the method of the present invention can be best described by reference to a particular operating procedure as illustrated in the drawing which is a diagrammatical sketch of a well bore equipped with a useful tubing arrangement and a container at the top of the well for holding and introducing into the bore the material which is reactive with water to produce the spontaneously ignitable reaction product.

In the embodiment of the drawing the well is 825 feet deep to the top of the oil sand and a well head pressure of 750 lbs. will force gas freely into the oil sand. A 2-inch steel tubing 1 is cemented at 2 in a 6-inch bore with a mix from 60 sacks of cement, and the tubing extends down to the oil sand. Below the lower end of the tubing is a bore hole several feet in height. Inside of tubing 1 is placed a $\frac{3}{4}$ -inch diameter steel tubing string 3 which reaches from near the oil sand through the well head 4 extending across tubing 1. Primary air at 750 p.s.i.g. pressure and at the rate of 1000 cubic feet per hour (STP) enters the well through valved $\frac{3}{4}$ -inch diameter steel pipe 5 which goes into tubing 3 just above the well head 4. When natural gas is used, it is preferably about 5 to 15 volume percent of its mixture with the primary air. Gas which is essentially methane is supplied at 750 p.s.i.g. pressure and at the rate of 80 cubic feet per hour (STP) through a valved $\frac{1}{4}$ -inch steel line 6 entering tubing 1 just below the well head 4. Line 6 continues down in the annulus between tubing strings 1 and 3 and enters tubing 3 a short distance, for instance 5 feet, from its lower end.

On the top of tubing 3 is a container 8 holding solid particulate commercial calcium phosphide (Baker and Adamson) which contains some calcium pyrophosphate. The solid particles are for the most part from $\frac{1}{16}$ to $\frac{1}{4}$ inch at the largest diameter. The container is isolated from tubing 3 by valve 7 and can be filled by way of valved line 13. Entering line 5 is a valved $\frac{1}{4}$ -inch steel line 9 through which water is injected into the primary air. Secondary air under a pressure of 750 p.s.i.g. and at

a rate of 4000 cubic feet per hour (STP) is passed into valved 2-inch steel line 10 entering tubing 1 below the well head 4. Thermowell 11 is located at the lower end of tubing 3 to follow the temperatures during the lighting procedure and it houses a thermocouple (not shown). The leads from the thermocouple pass through thermowell 11 to the surface at 12.

In operation the primary air, secondary air and hydrocarbon fuel flows are started in lines 5, 10 and 6, respectively. The valve 7 is then opened to admit to tubing 3 all of the 300 grams of calcium phosphide in container 8 and during this admission the flow rate of primary air through line 5 is 3000 (STP) cubic feet per hour. Immediately after the phosphide is injected, valve 7 is closed, the flow rate in line 5 is dropped back to 1000 (STP) cubic feet per hour and 1/2 gallon of water is charged by way of line 9 at the rate of 7 gallons per minute. During the passage of the phosphide and water down the tubing a reaction between these materials is initiated and the resulting mixture of mono- and diphosphine is combusted in the primary air in the lower end of tubing 3. This combustion then initiates burning of substantially all of the hydrocarbon fuel and another portion of the fuel would be combusted when it contacts the secondary air if insufficient primary air is used. When the temperature reaches a steady state at the lower end of tubing 3 to indicate the combustion of the hydrocarbon fuel is well established, no further water and phosphide injections are required. If desired, the lower ends of tubings 1, 3 and 6 can be made of stainless steel or other heat resisting metals.

Although my method has been described in conjunction with the system of the drawing, it can be effected in a number of other ways. As examples, the water might be injected with the primary air and the phosphide with the hydrocarbon fuel or vice versa. If tubing sizes permit, the water and phosphide could both be injected with the fuel with the water injection following that of the phosphide as in the system of the drawing.

In the method of this invention the heating of the stratum can be continued as long as desired, and the character of the combustion and the temperature of the surrounding formation can be followed as by analysis of combustion gases taken from an adjacent output well (not shown). In well lighting procedures the heating will usually be continued until the temperature of the adjacent stratum is in the range of 400° to 1200° F. for at least a 2-foot radius around the well bore so that upon supplying a free oxygen-containing gas a combustion wave will be maintained in the formation. The operator may choose to provide extraneous fuel while propagating the heat wave and the combustion wave in the formation.

In my method it is often advantageous that the reactive chemical be a solid comprised substantially of granular or macrosize particles, for instance having at least one dimension of not less than about $\frac{1}{32}$ of an inch. Finely divided material, e.g. phosphides, tend to stick to and react in the upper portions of the tubing. Also, the finely divided solid can plug the tubing and may have such a short reaction time that no substantial amount of spontaneously ignitable product will be made available in the lower regions of the well where burning is usually described. The upper limit on particle size can vary considerably with a primary factor being that the particles must be able to pass through the tubing. Preferably, macrosized solid in which substantially all of the particles have dimensions of not more than about $\frac{1}{4}$ of an inch is employed. In the system of the drawing there has been some indication that the solid phosphide particles start reacting with the water before they reach the lower end portion of the burner tubing so in order to insure the production and combustion of the phosphine, it is preferred that the particles have one dimension of at least about $\frac{1}{8}$ of an inch.

Generally, the amount of gaseous or liquid hydrocarbon fuel supplied to the well bore will be such that its mixture with all of the oxygen-containing gas available will have a heat of combustion of less than about 40 B.t.u.'s per cubic foot. Accordingly, when employing air and a hydrocarbon gas of 1000 B.t.u. per cubic foot quality, the latter is preferably not greater than about 4 volume percent of the total air provided. With lower B.t.u. hydrocarbon fuels increased volumes of fuel

can be used to maintain a heat of combustion of about 15 to 40 B.t.u.'s per cubic foot of total fuel and air mixture. The quantity, if any, of secondary gas supplied will depend upon the desired temperature of the final gas mixture. Whether the secondary gas be inert, air or hydrocarbon fuel it serves primarily to reduce the temperature of the combustion products, for instance to avoid formation spalling and destruction of metal. It may be desirable to heat the well with a rich fuel-air mixture, i.e. one in which the amount of oxygen is insufficient to burn all of the hydrocarbon fuel. This will avoid obtaining from the output well recycle gases containing free oxygen which might give rise to explosions. Combustion in this case should be essentially complete in the primary burner which would be the case where I supply, for instance 1000 cubic feet per hour of primary air, 80 cubic feet per hour of B.t.u. fuel gas and 4000 cubic feet per hour of hydrocarbon or inert secondary gas flow to provide a mixture of combustion products and secondary gas, having a temperature below 1000° F. Should it be desired to heat the stratum through a liner then the fuel-rich gas total mixture with substantially no free oxygen could maintain mix temperatures suitable for liner use without incurring the possibility of obtain deleteriously high temperatures due to the presence of carbon and free oxygen.

Although the method of the present invention has been described mainly with reference to the use of calcium phosphide, other materials which react with water to give a spontaneously ignitable product can be employed. A number of such materials are known, e.g. sodium, potassium and the metal phosphides, particularly those of metals having atomic numbers up to about 40. The various useful phosphides include those of the metals of Group I, such as sodium and lithium phosphides, and the Group II metal phosphides, for instance those of beryllium and magnesium. Aside from the alkali metal phosphides of Groups I and II, among the other metal phosphides which can be employed are those of aluminum and arsenic. These latter phosphides react moderately fast with water to provide a phosphine-containing product but if desired the speed of these reactions can be enhanced by the use of ignition promoters such as nitric oxide. Such promoters also can be employed with the alkali metal phosphides; however, they will usually not be required.

In the description of my method I have employed the term "phosphine" to designate both monophosphine and diphosphine. As previously noted the mixture obtained through the reaction of calcium phosphide and water contains both mono- and diphosphine, and it is believed that the latter is particularly effective towards making the mixture spontaneously ignitable in a free oxygen-containing gas at moderate temperatures, say 50 to 100° F., which exist in a great many well bores. Monophosphine is also spontaneously ignitable in a free oxygen-containing gas, but if diphosphine be not present, well bore temperatures of at least about 150° F. are advantageous. I prefer, therefore, to generate in the well bore diphosphine or mixtures of mono- and diphosphine, and when such mixtures are provided the diphosphine can ignite at a low temperature to promote the combustion of the monophosphine.

It is claimed:

1. In a method for lighting and continuing combustion of a hydrocarbon fuel in a well bore penetrating a sub-

terranean formation, the steps comprising introducing a moving fluid stream of hydrocarbon fuel into the well bore, introducing into the well bore a metal phosphide in a moving fluid stream, introducing water into the well bore in a moving fluid stream to provide contact between the metal phosphide and water to produce a spontaneously combustible reaction product in the vicinity of the desired location of lighting, contacting the spontaneously combustible reaction product with an oxygen-containing gas to provide combustion and said combustion serving to initiate and continue combustion of the hydrocarbon fuel.

2. The method of claim 1 in which both the metal phosphide and the water are introduced in one of the hydrocarbon fuel and oxygen-containing gas, the introduction of the water immediately following that of the metal phosphide.

3. The method of claim 1 in which there is supplied insufficient oxygen to provide combustion of all of the hydrocarbon fuel.

4. The method of claim 1 in which a secondary gas is introduced into the bore to reduce the temperature of the combustion products.

5. The method of claim 1 wherein the metal of the metal phosphide has an atomic number up to about 40.

6. The method of claim 5 wherein the metal phosphide is calcium phosphide.

7. In a method for lighting and continuing combustion of a hydrocarbon fuel in a well bore penetrating a subterranean formation, the steps comprising introducing into said bore a hydrocarbon fuel, oxygen-containing gas and a moving stream of macrosized metal phosphide particles, capable of reacting with water to produce spontaneously combustible phosphine, with at least one of the hydrocarbon fuel and oxygen-containing gas, contacting the phosphide with water in the vicinity of a desired location of lighting to produce said phosphine, said oxygen-containing gas contacting said phosphine to provide combustion and said combustion serving to initiate and continue combustion of the hydrocarbon fuel in said oxygen-containing gas.

8. The method of claim 7 in which the contacting of the water and the phosphide produces a mixture of mono- and diphosphine.

9. The method of claim 7 in which both the phosphide

and the water are introduced in one of the hydrocarbon fuel and oxygen-containing gas, the introduction of the water immediately following that of the phosphide.

10. The method of claim 7 wherein the metal of the metal phosphide has an atomic number up to about 40.

11. The method of claim 10 wherein the metal phosphide is calcium phosphide.

12. In a method for lighting and continuing combustion of a hydrocarbon fuel in a well bore penetrating a

15 subterranean formation, the steps comprising introducing into said bore through a first tubing an oxygen-containing gas stream, introducing hydrocarbon fuel through a second tubing in said bore which enters the first tubing near its lower end, introducing into said oxygen-containing gas stream, a stream of macrosize metal phosphide particles capable of reacting with water to produce a spontaneously combustible phosphine, and immediately thereafter reducing the rate of flow of the oxygen-containing gas stream and introducing water into said oxygen-containing gas stream to produce the spontaneously combustible phosphine in the vicinity of a desired location of lighting, said phosphine combusting in said oxygen-containing gas stream, thereby initiating and continuing combustion of the hydrocarbon fuel.

20 13. The method of claim 12 in which a gas stream is injected into the bore around said first tubing to reduce the temperature of the combustion products.

14. The method of claim 12 in which the contacting of the water and the phosphide produces a mixture of mono- and diphosphine.

15. The method of claim 12 wherein the metal of the metal phosphide has an atomic number up to about 40.

16. The method of claim 15 wherein the metal phosphide is calcium phosphide.
